UNITED STATES PATENT OFFICE.

JOSEPH G. MOOMY, OF ERIE, PENNSYLVANIA.

WRENCH MECHANISM.

1,345,619.

Specification of Letters Patent.

Patented July 6, 1920.

Application filed February 28, 1919. Serial No. 279,760.

To all whom it may concern:

Be it known that I, JOSEPH G. MOOMY, a citizen of the United States, residing at Erie, in the county of Erie and State of Pennsylvania, have invented new and useful Improvements in Wrench Mechanism, of which the following is a specification.

This invention relates to wrench mechanism and consists in certain improvements 10 in the construction thereof as will be hereinafter fully described and pointed out in the claims.

In the assembling of tubes for pneumatic tires it is necessary to apply a valve stem 15 and to secure the stem in place by a nut. This nut is run down a rather long stem and should exert an approximately uniform pressure on the parts to assure a complete closure on the stem. The present invention 20 is particularly designed for accomplishing this purpose.

The invention is illustrated in the accompanying drawings as follows:—

Figure 1 shows a side elevation of the 25 wrench, partly in section, on the line 1—1 in Fig. 2.

Fig. 2 an end elevation of the wrench.

Fig. 3 a section on the line 3—3 in Fig. 1.

1 marks a tube, 2 a valve stem for the 30 tube, 3 a head on the valve stem, 4 a closure plate on the valve stem, and 5 a nut which is usually placed on the valve stem for securing the stem in place on the tube.

A drive wrench 6 is mounted on a sleeve 35 7. The sleeve is frictionally driven from a gear 9. The gear has a screw-threaded flange 11 extending from it on which a flange nut 10 is secured, the flange nut operating on the flange 12 of the sleeve 7 and holding the flange 12 with adjusted tension 40 against a friction washer 12. It will be readily seen that as the gear is rotated the drive wrench is rotated with a yielding pressure which may be adjusted through the friction device just described.

A holding wrench 13 extends through a perforation 14 in a mounting 15. The holding wrench has a shoulder 16 which engages the mounting at one end of the perforation 50 and is provided with a nut 17 by means of which it is clamped on the mounting. A key 18 is also provided for preventing the holding wrench turning in the mounting.

The holding wrench has a tapered opening 55 19 leading to the wrench socket 20, the

wrench socket being shaped to engage the flats usually provided on valve stems 2.

A gear 21 is mounted on the drive shaft 22 of a motor 23. The gear 21 meshes with the gear 9 and is as the wrench is ordinarily 60 operated constantly in motion. The motor 23 is mounted on a base 24 from which the mounting 15 extends.

In operation the operator starts a nut on the stem 2, inserts the stem in the wrench 65 5 and as the nut progresses the stem is carried into the socket 20 of the holding wrench which holds the stem 2 and at the same time locates the head and plate on the stem in proper relation to the tube 1. As the nut 70 reaches the plate 4 the jar and tendency to turn the stem out of place is prevented by the holding of the stem through the action of the holding wrench. The nut is turned up to give any clamping action desired by 75 adjusting the flange nut 10 so as to create more or less friction between the friction surfaces between the flange 12 and the face of the gear 9.

What I claim as new is:—

1. In a wrench mechanism, the combination 80 of a driving wrench; a yielding drive mechanism having a predetermined driving engagement for said driving wrench; and a holding wrench, the holding wrench being mounted with relation to the driving wrench to hold a screw on which a nut is being driven by the driving wrench.

2. In a wrench mechanism, the combination 85 of a driving wrench; a friction drive mechanism having a predetermined driving engagement for said driving wrench; and a holding wrench, the holding wrench being mounted with relation to the driving wrench to hold a screw on which a nut is being driven by the driving wrench.

3. In a wrench mechanism, the combination 90 of a mounting; a holding wrench secured to said mounting; a drive gear journaled on the holding wrench; and a driving wrench frictionally driven from the drive gear and having a predetermined driving engagement, said holding wrench being in alignment with the driving wrench and in position to receive a screw stem inserted in 100 the driving wrench.

In testimony whereof I have hereunto set my hand.

JOSEPH G. MOOMY.
